(57) CLAIM

The ornamental design for a portable searchlight, as shown and described.

DESCRIPTION

FIG. 1 is a perspective view of a portable searchlight showing our new design;

FIG. 2 is a front view thereof;

FIG. 3 is a rear view thereof;

FIG. 4 is a left-side elevational view thereof;

FIG. 5 is a right-side elevational view thereof;

FIG. 6 is a top view thereof; and,

FIG. 7 is a bottom view thereof.

The matter shown in broken lines is shown for illustrative purposes only, and forms no part of the claimed design.
